PETER CARMICHAEL FORREST AND JAMES SAMUEL FORREST, OF TORONTO, ONTARIO,
CANADA.

CINDER-SIFTER.

1,364,926.

Specification of Letters Patent. Patented Jan. 11, 1921.

Application filed March 18, 1920. Serial No. 366,829.

To all whom it may concern:

Be it known that we, PETER CARMICHAEL FORREST, painter, and JAMES SAMUEL FORREST, motorman, both subjects of the King 5 of Great Britain, residing at Toronto, in the county of York, Province of Ontario, Canada, have invented certain new and useful Improvements in Cinder-Sifters, of which the following is the specification.

10 Our invention relates to improvements in cinder sifters and the object of the invention is to devise a means for automatically separating the cinders from the ash simultaneously with the operation of shaking the 15 furnace grates, and it consists essentially in the arrangement and construction of parts as hereinafter more particularly explained.

Figure 1 is a sectional view through the ash pit of the furnace and showing the grate 20 bars in position.

Fig. 2 is a longitudinal sectional view through Fig. 1.

Fig. 3 is a sectional plan view taken on line 3—3, Fig. 1.

25 Fig. 4 is a fragmentary view of a portion of the ash pit showing the lower draft door leading into the ash pit and our shaker in position.

In the drawings like characters of reference indicate corresponding parts in each figure.

1 indicates an ash pit of a furnace which is provided with the usual draft opening 2 and draft door 3 which is controlled by the 35 chain 4 in the usual manner. 5 are the grate bars of the furnace, the center bars being provided with the usual socketed trunnion ends 6 into which the inner end of the ash pit lever 7 extends in order to shake the 40 grates. 8 and 9 are U-bars which are supported in suspended position across the ash pit 1. The side arms 10 and 11 extend upward in proximity to the side walls of the furnace ash pit and are provided with 45 clamping bolts 12 and 13 which pass through the arms 10 and 11 and bear against the side walls of the ash pit and when tightened in position firmly hold the U-bars 8 and 9 suspended. 14 and 15 are directing plates 50 which are carried by or formed integral with the side arms 10 and 11 of the U-bars 8 and 9. The lower edges of the directing plates 14 and 15 are fingered as indicated at 16. 17 is an H-frame which comprises two side

angle bars 18 and 19 which slidably rest 55 upon the horizontal portions of the U-bars 8 and 9. The side bars 18 and 19 are connected together by a cross bar 20, the cross bar 20 being rigidly secured to the side bars 18 and 19 so as to form the H-frame. 21 is 60 a lever pivoted at its inner end to the cross bar 20 as indicated at 22, Fig. 2 and intermediate of its length to the horizontal portion of the U-bar 8 as indicated at 23. 24 is a supplemental lever provided at its inner 65 end with a socket 25 into which the outer end of the lever 21 fits. It will be noted on referring particularly to Fig. 2 that the lever 21 is entirely within the ash pit and that when the supplemental lever 24 is fitted 70 on the outer end of the lever 21, it extends through the draft opening 2 of the ash pit when the draft door 3 is in the open position. The shaking lever 7 is provided with a downward extension 25. 26 is a link which 75 is preferably formed of a bar twisted intermediate of its length so that one end of the bar is at right angles to the other. One end of the link 26 is pivotally secured at 27 to the lower end of the downward extension 25 80 of the lever 7 and the opposite end of the link is provided with a depending pin 28 which extends through a perforation 29 formed in the end of the supplemental lever 24. 30 is a basket which is formed of woven 85 wire mesh so as to form a sifter for the ashes. The inner end of the basket is formed with an open end which bears against the back wall of the ash pit. When in position the basket fits between the opposing angle 90 bars 18 and 19 so that the basket moves with the H-frame when operated. The basket is also provided with a casting 31 suitably secured thereto, having a socket projection 32 adapted to receive the inwardly projecting 95 portion of the shaking lever 7 when removed from the socketed trunnions 6 according to the usual practice. The lower draft door 3 is then raised to the open position as indicated in Figs. 2 and 4. The supplemental 100 lever 24 is then engaged with the lever 21, such supplemental lever extending through the draft door opening. The pin 28 is then inserted in the perforation 29 connecting the portion 25 of the shaking lever 7 to the supplemental lever 24. The shaking lever 7 is 105 then operated in the usual manner. The shaking of the lever 7 causes the ashes to

fall into the basket 30 which at the same time is rapidly reciprocated back and forth crosswise of the ash pit by reason of the action of the shaking lever 7 through the dependent portion 25, link 26, supplemental lever 24 and lever 21, thereby reciprocating the H-frame upon the horizontal portions of the U-bars 8 and 9 and shaking the basket and causing the fine ash to drop into the ash pit and retaining the cinders therein. As soon as the shaking operation is completed the lever 7 may be removed together with the supplemental lever 24, the supplemental lever 24 and lever 7 being then separated by withdrawing the pin 28, the inwardly projecting portion of the lever 7 may be then inserted in the socket 32 after the ash pit door has been opened and the basket 30 removed, the cinders being then dumped from the basket into the fire pit of the furnace on to the fire bed, this operation being readily performed by reason of the inner end of the basket being left open.

From this description it will be seen that we have devised a very simple device whereby the ashes, as they are shaken from the furnace may be simultaneously sifted and the cinders separated therefrom removed and replaced in the fire. If it is found necessary to shake the cinders in the basket more than is done by the above operation the shaking lever 7 may be removed and separated from the supplemental lever 24, the supplemental lever 24 being left in engagement with the lever 21. The lever 24 may then be operated by hand to perform this extra shaking. It has, however, been found in practice that the sifting operation performed when shaking the grates is sufficient to separate the cinders from the ash.

What we claim as our invention is:

1. In a furnace, the combination with the ash pit, grate bars and shaking levers, of a supporting structure located beneath the grate bars, a shaking basket slidably supported upon the supporting structure, and a lever mounted intermediately of its length upon the supporting structure and connected at its inner end with the shaking basket, an arm depending from the shaking lever, a supplemental lever engaging the lever of the shaking basket and extending through the draft opening of the ash pit, and means for engaging the depending portion of the shaking lever and the supplemental lever whereby the supplemental lever is reciprocated by the operation of the shaking lever.

2. In a furnace, the combination with the ash pit, grate bars and shaking levers, of a supporting structure located beneath the grate bars, a shaking basket slidably supported upon the supporting structure, a lever mounted intermediately of its length upon the supporting structure and connected

at its inner end with the shaking basket, an arm depending from the shaking lever, a supplemental lever engaging the lever of the shaking basket and extending through the draft opening of the ash pit, and a link pivotally connected at one end to the depending portion of the shaking lever and engaging the supplemental lever with the opposite end.

3. In a furnace, the combination with the ash pit, grate bars and shaking levers, of a supporting structure located beneath the grate bars, a shaking basket slidably supported upon the supporting structure, a supplemental lever pivotally mounted intermediately of its length upon the supporting structure and pivotally connected with the shaking basket at its opposite end, a supplemental lever engaging the outer end of the shaking basket lever and extending through the draft door of the furnace, and having a perforation at its outer end, an arm depending from the grate bar shaking lever, a link pivotally connected to the lower end of such arm, a pin depending from the opposite end of the link and adapted to extend through the perforation of the supplemental lever.

4. In a furnace, a supporting structure adapted to fit within the ash pit and provided with cross bar portions, a frame comprising opposing angle bars connected together, a shaking basket fitted between the opposing angle bars, a lever pivoted at one end upon one of the cross bars of the supporting structure and pivotally connected at its opposite end to the frame holding the shaking basket, and means extending through the draft door for operating the lever.

5. In a furnace, a supporting structure adapted to fit within the ash pit and provided with cross bars, an H-frame comprising opposing angle bars slidably resting upon the cross bars, and a cross bar connecting the angle bars together intermediately of their length, a lever pivotally supported upon one of the cross bars of the supporting structure and at the opposite end to the cross bar of the H-frame, and means extending through the ash pit door of the furnace for operating the lever.

6. In a furnace, a supporting structure comprising a pair of U-bars extending between the side walls of the ash pit of the furnace with the arms of the bars disposed vertically, means for clamping the vertical arms to the side walls of the ash pit, an H-frame slidably supported by the U-bars, a shaking basket held within the H-frame, and means extending through the draft door of the furnace for reciprocating the shaking basket.

7. In a furnace, the combination with the ash pit and grate bars, of a removable sup-

porting structure suspended beneath the grate clear of the bottom of the ash pit, a sifting basket mounted on the supporting frame and free to reciprocate laterally thereon, a lever for reciprocating said basket, pivoted at its inner end to an intermediate portion of said basket and intermediate its ends to the forward portion of said frame, a supplementary actuating lever for the basket

having a socket at one end receiving the outer end of said first lever.

8. The combination with the construction recited in claim 7, of a grate shaking lever provided with an extension, and means for releasably coupling the supplementary actuating lever to said extension.

PETER CARMICHAEL FORREST.
JAMES SAMUEL FORREST.
